Frederick W. Andrew

BY
Adolph A. Thomas
ATTORNEY

UNITED STATES PATENT OFFICE.

FREDERICK W. ANDREW, OF GLEN HEAD, NEW YORK, ASSIGNOR TO EISEMANN MAGNETO CORPORATION, OF BROOKLYN, NEW YORK, A CORPORATION OF NEW YORK.

MAGNETO DISTRIBUTOR.

Original application filed October 3, 1921, Serial No. 504,934. Divided and this application filed April 10, 1924. Serial No. 705,463.

To all whom it may concern:

Be it known that I, FREDERICK W. ANDREW, a citizen of the United States, and a resident of Glen Head, Long Island, county 5 of Nassau, and State of New York, have invented certain new and useful Improvements in Magneto Distributors, of which the following is a specification.

My invention relates to ignition magnetos, 10 and its object is to provide new and useful distributor mechanism, which is readily installed and removed, and which embodies improved features of construction, as will subsequently appear. In the accompanying 15 drawings,

Fig. 1 shows the distributor end of a magneto equipped with my invention, certain parts being shown in cross-section for clearness;

20 Fig. 2 is an end view of the magneto, with the distributor block removed and with the distributor disk shown in section approximately on line 2—2 of Fig. 1;

Fig. 3 is an inside face view of the distributor block;

25 Fig. 4 is a cross-section approximately on line 4—4 of Fig. 3;

Fig. 5 is a face view of the distributor disk mounted on the armature shaft of the magneto;

30 Fig. 6 is a detached perspective view of the metallic contact member embedded in the distributor disk of Fig. 5;

Fig. 7 is an enlarged view of the screw 35 for fastening the cable or conductor in the distributor block; and

Fig. 8 is an end view of the armature shaft to show the shoulder or cutaway portion thereof.

40 For the sake of simplicity and convenience, I have assumed that the distributor mechanism shown in the drawings is applied to an ignition magneto for a two-cylinder internal combustion engine. I want it understood, however, that my invention is 45 applicable to a magneto for single and multi-cylinder engines generally, and especially for magnetos which can be changed for use on engines having different number of cylinders.

The magneto M represents any suitable construction of ignition magneto, having an armature A mounted to rotate or oscillate

between the poles of the magnet. The distributor end 1 of the armature shaft is of 55 insulating material and has embedded therein a conductor 2 which terminates in a button 3. As shown in Fig. 1, this button is practically flush with the outer end of the armature shaft. The projecting end of this 60 shaft has a cutaway section to form a shoulder 4 (see Fig. 8), for a purpose that will presently become clear.

On the projecting end of the insulated 65 armature shaft 1 is mounted a distributor disk 5. This disk, which is of hard rubber or other insulating material, has an opening 6 formed with a shoulder 7. When the disk 5 is inserted on the shaft 1, the shoulder 7 fits against the correspondingly arranged 70 shoulder 4 on the shaft, whereby the disk 5 is locked to the armature shaft so as to rotate therewith, at the same time being free to be removed. The distributor disk 5 has embedded therein a segmental or arc-shaped 75 contact 8, which has an extension 9 terminating in a contact button 10. The contact 8 is practically flush with the outer face of the disk. When the distributor disk is in place on the magneto shaft, the button 10 80 is in firm contact with the button 3 of the magneto shaft, as shown in Fig. 1.

A distributor block, indicated as a whole 85 by D, is firmly mounted on the end plate 11 of the magneto, and is held in position by a spring arm 12 pivoted on a stud 13. The block D is of suitable insulating material and is formed with a chamber 14, into which projects a pair of contacts or brushes 15, 90 usually of carbon. These brushes are each slidably mounted in a hollow metal plug 16 embedded in the insulating block. A light spring 17 presses each brush outwardly 95 against the face of disk 5 and therefore against the rotary segmental contact 8. The reason why two collector brushes 15 are shown is because, as previously stated, it has been assumed that the magneto is for a two-cylinder engine.

100 A cable or conductor 18, encased in suitable insulation 19, is electrically connected to each metal plug 16. The cables pass each through an opening 20 in the distributor block D and the frayed ends 21 of the wires 105 which constitute the cable are pushed tight against the metal plug 17. Each cable leads

to the insulated terminal of a spark plug. I provide very simple and efficient means for securely fastening the cables in the insulator block, and yet permitting easy removal thereof when necessary. This means comprises a set screw 22 having a pointed end 22', which enters the insulation 19 surrounding the high-tension cable 18. It will be noticed that the screw 22 pierces the insulation of the cable at an angle in a direction to oppose a force tending to pull the cable out of its socket. It will also be seen that tightening of the screw tends to push the inner end of the cable against the metal plug 16. The screw 22 may be entirely concealed in the opening 23 in the insulator block, as shown in Fig. 4. The screw 22 is not a current-carrying member, and its sole function is to hold the high-tension cable in electrical contact with the metal plug 16. For this reason the screw 22 may be made of metal or of insulating material. I prefer to make the screw 22 of fiber or other hard insulating material suitable for that purpose. This prevents the danger of a possible short-circuit between the high-tension circuit and the grounded parts through moisture. As seen in Fig. 4, the screw-hole 23 has an enlargement which forms an annular flange or shoulder adapted to act as a stop for the head of the screw, thereby positively limiting the inward movement of the screw.

The distributor block D is provided with a circular flange or shoulder 24 adapted to fit against a corresponding flange or shoulder 25 on the end plate 11, whereby the distributor block is readily centered on the end plate. If desired, the distributor block may also be provided with a lug 26 arranged to enter a notch or recess 27 in the end plate 11, when the distributor block is properly positioned on the magneto. The lug 26 and notch 27 thus insure a correct positioning of the distributor block on the magneto.

It will be seen from the foregoing that the distributor block D and disk 5 are readily attached in proper position on the magneto and as easily removed therefrom. This makes it a very simple matter to change the magneto from one number of cylinders to a different number of cylinders, thereby adapting the magneto for use on single-cylinder engines as well as on multi-cylinder engines.

While I have herein shown and described a specific construction, I do not intend to be limited to the details set forth. It is obvious that changes and modifications may be resorted to and yet be within the scope of my invention as defined in the appended claims.

This application is a division of my co-pending parent application Serial Number

504,934, filed October 3, 1921. The filing of the present application is due to a final requirement of division in the parent case.

What I claim as my invention is:

1. As a new article of manufacture for use in ignition magnetos, a distributor disk of insulating material having a hole or recess extending axially from one face thereof to receive one end of a magneto shaft, and a contact member embedded in said disk so as to be substantially flush with the other face of said disk, said contact member having an extension which terminates in said hole or recess. 70

2. As a new article of manufacture for use in ignition magnetos, a distributor disk of insulating material having a non-circular hole or recess extending axially from one face thereof to receive one end of a magneto shaft, and a segmental or arc-shaped conducting strip embedded in said disk so as to be substantially flush with the other face of said disk, said strip having an integral extension which terminates in a contact button in said hole or recess. 80 85

3. In an ignition magneto, a rotatable armature mounted in the magneto frame, an insulated shaft projecting from one end of said frame, a high-tension conductor embedded in said shaft and terminating in a contact at the outer end of said shaft, in combination with an insulated distributor disk having a hole or recess adapted to fit snugly over the projecting part of said insulated shaft so as to rotate therewith, said disk having a metallic member arranged to engage said contact when the disk is in operative position on the shaft. 95 100

4. In an ignition magneto, a rotatable armature mounted in the magneto frame, an insulated shaft projecting from one end of said frame, a high-tension conductor embedded in said shaft and terminating in a contact at the outer end of said shaft, in combination with an insulated distributor disk having a hole or recess adapted to fit snugly over the projecting part of said insulated shaft, said disk and shaft being provided with cooperating means which lock the disk against rotary movement on the shaft but permit the disk to be readily slid on and off the shaft, said disk having a metallic member arranged to engage said contact when the disk is in operative position on the shaft. 105 110 115 120

5. In a distributor block for use in ignition magnetos, an insulated body having a contact member embedded therein, an insulated cable or conductor passing through an opening in said body into electrical contact with said member, said body having a flanged screw-hole connecting with said cable opening, and a flanged pointed screw of insulating material secured in said hole in such position that the pointed end thereof 125 130

- penetrates said cable insulation and thereby locks the same against displacement, the flange on said screw cooperating with the flange in the screw-hole to form a positive 5 stop for the inward movement of the screw.
6. In a distributor block for use in ignition magnetos, an insulated body having a contact member embedded therein, an insulated cable or conductor passing through an 10 opening in said body into electrical contact with said member, said body having a screw-hole on the outside connecting with said cable opening at an angle thereto in a direction toward said member, and a pointed 15 screw of insulating material secured in said hole in such position that the pointed end thereof penetrates said cable insulation and thereby locks the same against displacement, the inclination of said screw relatively to 20 said cable being such that the screw resists an outward pull on the cable and tends to hold the cable against said contact.
7. In a distributor block for use in ignition magnetos, an insulated body having a 25 contact member embedded therein, an insulated cable or conductor passing through an opening in said body into electrical contact with said member, said body having a screw-hole on the outside connecting with 30 said cable opening, and a pointed screw of insulating material secured in said hole in such position that the pointed end thereof penetrates said cable insulation and thereby locks the same against displacement.
8. In an ignition magneto, an end plate 35 provided on its face with a circular shoulder having a notch or recess therein, a distributor block having on its face an annular flange arranged to engage with said shoulder to center said block on the magneto, a lug on said block projecting from said annular flange and arranged to enter said recess for locking said block against rotary movement on the end plate, and releasable means for holding said block 40 45 pressed against said end plate.
9. In an ignition magneto, a rotatable armature mounted in the magneto frame, an insulated shaft projecting from one end of said frame, a high-tension conductor embedded in said shaft and terminating in a contact at the outer end of said shaft, in combination with an insulated distributor disk having a hole or recess adapted to fit snugly over the projecting part of said insulated shaft so as to rotate therewith, said disk having a metallic member arranged to engage said contact when the disk is in operative position on the shaft, and a distributor block removably mounted over said disk 50 55 and having contacts arranged to be engaged by said metallic member.

FREDERICK W. ANDREW.
